UNITED STATES PATENT OFFICE

2,103,938

MANUFACTURE OF ELECTRIC INCANDESCENT LAMPS HAVING COILED-COIL FILAMENTS

Bernard Phineas Dudding and Reginald Edward
Leeds, Middlesex, England, assignors to General
Electric Company, a corporation of New
YorkApplication April 14, 1937. Serial No. 136,940
In Great Britain March 6, 1936

2 Claims. (Cl. 176—39)

This invention relates to the manufacture of electric incandescent lamps having coiled-coil filaments.

In the usual process of manufacturing these lamps, the conversion of the plain wire to the filament, ready for mounting in the lamp, is conducted wholly at temperatures much lower than the filament attains in operation. The filament is mounted in the lamp and then "aged" by passing current through it so as to heat it to a temperature higher than any to which it has been subjected during its formation from plain wire. It is well-known that the filament is apt to change its length during this final, or "aging" process; usually it contracts. This change of length is apt to be accompanied by the development of local irregularities of pitch, especially if the filament is supported at points intermediate between its ends by "pigtails," which may hamper free contraction. The object of this invention is to provide a method of supporting the filament which decreases the chance of serious irregularities arising from the change of length.

According to the invention the supports by which the filament is supported at points intermediate between its ends are loops, elongated in that direction in which the filament will tend to move relatively to the supports in virtue of its contraction on aging, but fitting the filament comparatively closely in the perpendicular direction.

Thus if the filament is to be mounted as a circular arc in a plane perpendicular to the axis of the lamp, and if the lamp is to be burnt with its axis vertical, the supports are loops elongated in the direction of the radius of the circle which passes through them, but fitting the filament more closely in the direction parallel to the axis of the lamp. The length of the loops in the elongated direction is preferably chosen so that, when the change of length is completed the filament fits somewhat closely into the end of the loop which it approaches during the change. By this means breakage of the filament owing to vibration is diminished.

It is to be observed that, if the loops are made in this manner, they would offer no support to the filament, if the lamp were burnt with its axis horizontal and with the filament below the axis. Accordingly this method of construction should not be adopted if it is likely that the lamp will be burnt in this position.

One embodiment of the invention will now be described in detail, by way of example, with reference to the accompanying drawing although,

apart from the elongated loops it follows a prevailing practice in the art. In the drawing, Fig. 1 is a perspective view of a lamp embodying the filament supporting means comprising our invention; Fig. 2 is a somewhat diagrammatic plan view of the filament and its supporting structure; and Fig. 3 is a perspective view showing a portion of the coiled-coil filament and one of the supporting loops therefor. The lamp concerned is a 240 volt 40 watt lamp.

The diameter of the wire is 0.0232 mm.; it is wound on a primary molybdenum mandrel 0.045 mm. in diameter with a pitch of 0.038 mm. or 164 per cent. The secondary mandrel is 0.210 mm. in diameter and the pitch of the secondary helix is 0.176 mm. or 192 per cent; there are 153 turns in this helix, successive filaments being spaced along the mandrel. The filaments are heated on the mandrel to 1500° C. for ten seconds and cut to length; the mandrels are dissolved out.

Each filament is now mounted in a lamp, as shown in the accompanying drawing. 1 is the filament as originally mounted, with its ends supported by the leads 2, 3 and the part intermediate between the ends supported by the support wires 4 which are 0.1 mm. in diameter and are spaced 40° apart from each other and the ends. The inner ends 5 of the wires are held in the glass stud 6; the outer ends are formed into loops 7 lying in planes perpendicular to the plane of the drawing.

According to the invention these loops are not circular, as is usual, but are elongated in the radial direction. They are 2.25 mm. long in the radial direction and 1.25 mm. wide perpendicular to the plane of the drawing.

When the filament is mounted and the lamp evacuated and filled with gas, the filament is aged preferably with the plane of the drawing vertical and the stud above the filament. During aging the filament contracts 10.36 per cent in length, so that the pitch of the secondary helix becomes 0.158 mm. or 172 per cent.

It has been found that elongated loops can be made on automatic machines such as are used for making circular loops with only those modifications that are obvious to those skilled in the art.

What we claim as new and desire to secure by Letters Patent of the United States is:

1. In an electric incandescent lamp having an arcuately mounted coiled-coil filament securely held at its ends, means for supporting said filament intermediate its ends consisting of support wires having loops engaging said filament, said loops being elongated in the direction in which

the filament tends to move relatively to the supports by virtue of its contraction during aging but fitting the filament comparatively closely in the direction normal thereto.

5. 2. In an electric incandescent lamp having an arcuately mounted coiled-coil filament disposed in a plane normal to the axis of the lamp and securely held at its ends, means for supporting said filament intermediate its ends consisting of 10 support wires extending laterally outward from

said lamp axis and having loops engaging said filament, said loops being elongated in the said lateral direction to provide for movement of the filament relatively to the supports by virtue of its contraction during aging but fitting the filament comparatively closely in the direction parallel to the lamp axis. 5
